UNITED STATES PATENT OFFICE.

HUGO S. HASSELQUIST, OF FORT MADISON, IOWA, ASSIGNOR TO C. H. HANSON COMPANY, OF CHICAGO, ILLINOIS, A CORPORATION OF ILLINOIS.

COMBINATION SEAL.

Application filed October 15, 1923. Serial No. 668,470.

The invention has to do with seal-presses such as are used for affixing marks of various kinds in relief or intaglio upon impressionable sheet material.

5 The principal object of the invention is the provision of a novel seal-press in which is combined the advantages in manipulation possessed separately under diversified conditions of use by the so-called pocket, desk and stamp seal-presses.

Another important object of the invention is the provision of a novel seal-press which is characterized in its construction, arrangement and manner of operation by numerous 15 hereinafter described features serving, first, to permit ready assembling or disassembling of the component parts, second, to insure proper alignment of the component parts when assembled, third, to effect an extremely 20 high working pressure with almost negligible effort, fourth, to equalize the distribution of the working pressure, and fifth, to permit a stamped and consequently inexpensive fabrication of the larger component parts from 25 sheet metal.

Other objects and advantages which are not specifically referred to in this disclosure will be appreciated upon a full comprehension 30 of the construction, arrangement and manner of operation of the seal-press.

For the purpose of exemplification, one embodiment of the invention is presented in the accompanying drawings and in the following detailed description, but, as numerous 35 other modified embodiments are obviously also within the purview of the invention, the embodiment here presented is not to be considered as limiting the spirit of the invention short of its intended scope as defined by 40 the appended claims.

In the drawings—

Fig. 1 is a side view of the seal-press in open position;

Fig. 2 is another side view of the same in 45 closed position;

Fig. 3 is a top view of the same;

Fig. 4 is a section on the line 4—4 of Fig. 1;

Fig. 5 is a bottom view of the equalizing plate;

Fig. 6 is a section on the line 6—6 of Fig. 5;

Fig. 7 is a section on the line 7—7 of Fig. 1;

Fig. 8 is a section on the line 8—8 of Fig. 1;

Fig. 9 is a perspective view of the ram;

Fig. 10 is a perspective view of the rocker; and

Fig. 11 is a perspective view of the cover.

It will be observed in the drawings that the seal-press comprises a supporting frame 10; an impression die 11; an operating lever 12; a connection 13 between the die and the lever; an impression bed 14; and a connection 15 between the bed and the frame.

The supporting frame 10 is a sheet metal stamping of U-shaped cross section. One end of the frame is formed into an upper jaw portion 16 and a lower jaw portion 17, and the other end is formed into a reduced portion 18 which presents for selective use a handle grip 19 and a terminal support 20.

The impression die 11 includes a die head 21 and an associated ram 22. The die head 21 is disposed between the upper and lower jaw portions of the frame, and consists of a flat circular disk which presents a seal inscription 23 on its under face and a cylindrical attaching stud 24 on its upper face. The ram 22 is disposed between the parallel side walls of the upper jaw portion of the frame, and consists of a rectangular block which contains a cylindrical socket 25 in its under face for fixed engagement with the stud. The ram 22 is disposed between the parallel side walls of the upper jaw portion of the frame, and consists of a rectangular block which contains a cylindrical socket 25 in its under face for fixed engagement with the stud. The die head and the ram are adapted for reciprocating movement relative to the frame, and are guided in such movement by means of lugs 26 which extend inwardly from the side walls of the upper jaw portion into longitudinally extending grooves 27 formed in the sides of the ram. Additional grooves 28 are formed in the sides of the ram in order to permit removal of the die head and the ram from the frame. The grooves 28 extend perpendicularly from the grooves 27 at the locations of the lugs 26 in the grooves 27 when the die head and the ram are moved into an extreme position with the upper face of the die head against the under face of the upper jaw portion, and provide passages for the accommodation of the lugs 26 when the die head and the ram are withdrawn from the upper jaw portion while in their extreme position.

The operating lever 12 is a sheet metal stamping of inverted U-shaped cross section. One end of the lever is contained be-

tween the side walls of the upper jaw portion of the frame and is there pivotally mounted on a pin 29 which passes through aligned apertures in the side walls, and the 5 other end extends from the frame in a more or less diverging relation to the handle grip 19 of the same and presents a handle grip 30 which may be used either alone, when the frame is supported on a surface by its 10 terminal support 20, or in conjunction with the co-acting handle grip 19 when the frame is not supported on a surface. The lever is provided, at a point adjacent its pivotal axis, with a slightly offset portion on which 15 is mounted a freely rotatable cam roller 31 for cooperation with a portion of the connection 13 to be hereinafter described.

The connection 13 between the impression die 11 and the operating lever 12 consists of 20 a rocker 32 which occupies a slot 33 found in the upper portion of the ram 22 and protrudes from the slot at both ends of the same. One protruding end of the rocker is pivotally mounted on the upper jaw portion 25 of the frame by means of a pin 34 which passes through aligned apertures in the side walls; the other oppositely protruding end of the rocker is tapered and presents an inclined surface 35 for coaction with the cam 30 roller 31; the medial bottom portion of the rocker is downwardly convex and presents a segmental bearing surface 36 for the rocker against a flat thrust surface 37 of the ram; and the medial upper portion of the rocker 35 is upwardly convex and presents a segmental bearing surface 38 for coaction with two inwardly overlapping lips 39 on the top of the ram. A compressed spring 40 is housed 40 within the frame and engages with the rocker at a point below the point of engagement of the cam roller in order to normally maintain the free end of the rocker in its elevated position.

The impression bed 14 includes a flash 45 plate 41 and an equalizing plate 42. The flash plate is circular in shape, and is provided with a depending skirt 43 which is cut away at diametrically opposed points in order to permit the flash plate to straddle 50 the lower jaw portion 17 of the frame without directly contacting with the same. The remaining uncut portions of the skirt 43 constitute spaced supports 44 on opposite sides of the frame for use in conjunction with the 55 terminal support 20 when it is desired to rest the seal-press upon a plane surface. The upper surface of the flash plate is adapted to be coated in the usual manner with a composition 45 on which is presented a seal inscription complementary to that presented on the under face of the die head 21. The equalizing plate is circular in shape, and is contained within the skirt of the flash plate 60 in fixed contiguous engagement with the under surface of the same. A centrally dis-

posed segmental projection 46 and two or more pairs of studs 47 are formed in the under face of the equalizing plate. The segmental projection is adapted to seat at its opposite ends in transversely aligned 70 complementary notches in the upper surface of the lower jaw portion of the frame with the under surface of the equalizing plate in spaced relation to the lower jaw portion, and the pairs of studs are adapted to straddle 75 one of the two upturned edges of the lower jaw portion in order to position the equalizing plate in fixed angular relation to the lower jaw portion.

The connection 15 between the impression 80 bed and the frame consists of an anchor bolt 48. The upper end of the anchor bolt passes upwardly through an aperture in the segmental projection on the equalizing plate and is provided above the loosely encompassing aperture with a segmental head 49 which seats in the depression resulting from the pressed formation of the segmental projection, and the lower end of the anchor bolt passes downwardly to a threaded conical aperture in the bottom of the lower jaw portion and is engaged by an exteriorly threaded split conical nut 50 which is in turn engaged with the aperture in the jaw portion. The nut is screwed up tightly upon 95 the anchor bolt, and serves to hold the impression bed firmly down upon the lower jaw portion of the frame while permitting with friction a slight readjusting movement of the impression bed relative to the lower jaw 100 portion upon movement of the die head into compressive engagement with the upper surface of the flash plate. The split conical nut is wedged between the bolt and the encompassing aperture in the jaw portion, and the 105 wedged action results in a frictional constriction of the nut on the bolt serving to prevent the impression bed from working loose on its anchorage.

The pivoting pins 29 and 34, which were 110 referred to in connection with the detailed description of the operating lever 12 and the connection 13, are provided, intermediate their ends, with annular grooves 51. A curved cover plate 52 of spring material 115 spans the gap between the front and top edges of the side walls of the upper jaw portion of the frame, and is provided, at its ends, with laterally reduced tongues 53 which curve about the pivoting pins and seat in the annular grooves of the same. The cover plate is also provided, at opposite points along its side edges, with two downwardly bent clips 54 which seat in recesses in the side walls of the upper jaw 120 portion and serve to position the cover plate relative to the side walls.

The lugs 26 and the studs 47, which were 125 referred to in connection with the detailed description of the impression die 11 and the 130

impression bed 14, are preferably die-punched formations wherein the metal within certain areas on the opposite sides of the sheet of metal is caused to flow under pressure into projections of less area. These formations are economical to produce and are extremely durable.

The seal-press may be assembled in the following manner:

10 First, the impression bed, which includes the flash plate and the equalizing plate, is placed on the lower jaw portion of the frame and is secured in place by the anchor bolt which is engaged by the conical nut which in turn is engaged by the frame; second, the impression die, which includes the die head and the ram, is placed with the ram between the side walls of the upper jaw portion and with the die head against the under edges of the side walls and is pushed inwardly until the longitudinal grooves in the ram are in alignment with the lugs on the side walls, whereupon the impression die is pushed downwardly in its guides into contact with the impression bed; third, the rocker is inserted in the slot in the ram, and the pivot pin for the rocker is positioned; fourth, the operating lever is placed with one end between the side walls of the frame, and the pivot pin for the lever is positioned; and fifth, the cover plate is snapped into place with its ends about the pivot pins.

The seal-press may be disassembled in the following manner:

A pointed instrument of any suitable character is placed against the ends of the pivot pins and sufficient force is exerted against the pins by the instrument to spring the tongues on the ends of the cover plate out of the annular grooves and move the pins axially from their apertures, whereupon the cover plate, the operating handle and the rocker will be released from the frame. The impression die, which includes the die head and the ram, may be released by moving the same first upwardly against the under surface of the upper jaw portion, and then laterally, and the impression bed may be released by unscrewing the conical nut from the anchor bolt.

Under those conditions of use wherein it is more convenient to carry the seal-press to the sheet of impressionable material than to carry the sheet to the seal-press, the seal-press may be gripped in one's hand and manipulated after the fashion of the pocket seal-press; and, under those different conditions of use wherein it is more convenient to carry the sheet of impressionable material to the seal-press than to carry the seal-press to the sheet, the seal-press may be placed on a suitable supporting surface and manipulated after the fashion of either the desk or stamp seal-press.

In view of the foregoing detailed description of the construction and arrangement of the seal press, any detailed explanation of the manner in which the seal press operates is unnecessary. It will be appreciated that the impression die has a reciprocating movement in the frame to and from the self-aligning impression bed, and that the movement of the impression die is translated from the oscillating movement of the operating lever through an unusually efficient double fulcrum arrangement.

I claim:

1. In a seal-press, a supporting frame, a movable impression die, a stationary impression bed, and a trunnion connection between the frame and the bed for causing the bed to align with the die upon movement of the die into compressive engagement with the bed.

2. In a seal-press, a supporting frame, a movable impression die, a stationary impression bed, a segmental projection across the back of the bed adapted to seat against a portion of the frame for causing the bed to align with the die upon movement of the die into compressive engagement with the bed, and means for maintaining the bed and frame in non-separable engagement.

3. In a seal-press, a supporting frame, a movable impression die, a stationary impression bed, a segmental projection at the back of the bed adapted to seat against two conforming relieved portions of the frame for causing the bed to align with the die upon movement of the die into compressive engagement with the bed, and an anchor bolt for maintaining the bed and frame in non-separable engagement.

4. In a seal-press, a supporting frame, an impression die mounted for reciprocating movement relative to the frame, a stationary impression bed associated with the frame, an operating lever pivoted to the frame, and a rocker pivoted to the frame in camming engagement both with the lever and with a thrust surface associated with the die whereby to translate the oscillating movement of the lever into the reciprocating movement of the die under a multiplication of power.

5. In a seal-press, a supporting frame, an impression die mounted for reciprocating movement relative to the frame, a stationary impression bed associated with the frame, an operating lever pivoted to the frame, and a rocker pivoted at one end to the frame in camming engagement both at its free end with the lever and intermediate its ends with a thrust surface associated with the die whereby to translate the oscillating movement of the lever into the reciprocating movement of the die under a multiplication of power.

6. In a seal-press, a supporting frame, a

ram for an impression die mounted for reciprocating movement relative to the frame, a stationary impression bed associated with the frame, an operating lever pivoted to the frame, and a rocker pivoted at one end to the frame in camming engagement both at its free end with the lever and intermediate its ends with the ram whereby to translate the oscillating movement of the lever into the reciprocating movement of the die under a multiplication of power.

7. In a seal-press, a supporting frame having spaced side walls formed to provide a guideway, a ram for an impression die mounted for reciprocating movement in the guideway of the frame, means for limiting the movement of the ram in one direction when the seal press is assembled, and means for permitting the ram to be moved laterally out of guided engagement with the guideway when the limiting means is removed and the ram is moved to one end of its travel.

8. In a seal-press, a supporting frame having spaced side walls formed to provide spaced guide projections, a ram for an impression die mounted for reciprocating movement in the frame and having longitudinal grooves for sliding engagement with the projections, means for limiting the movement of the ram in one direction when the seal press is assembled, and transverse grooves in the ram connecting with the longitudinal grooves for permitting the ram to be moved laterally out of guided engagement with the projections when the limiting means is removed and the ram is moved to one end of its travel with the transverse grooves in alignment with the projections.

9. In a seal-press, a sheet metal supporting frame of U-shaped cross section adapted to serve either as a pedestal or as one of two coacting handles, a sheet metal operating lever of inverted U-shaped cross section pivotally associated with the frame and movable into or out of the channel of the same, impression means consisting of a mov-

able die and a stationary bed contained in cutaway portions in the sides of the frame at one end of the same, guiding means for the die on the spaced parallel walls extending above the impression means, anchoring means for the bed at the bottom of the channel portion extending below the impression means, and pedestal portions at the bottom of the bed on opposite sides of the frame.

10. In a seal-press, a supporting frame adapted to serve either as a pedestal or as one of two co-acting handles, an operating lever pivotally associated with the frame, impression means consisting of a movable die and a stationary bed contained in a cutaway portion of the frame at one end thereof, guiding means for the die on the portion of the frame above the impression means, anchoring means for the bed on the portion of the frame below the impression means, and pedestal portions at the bottom of the bed on opposite sides of the frame.

11. In a seal-press, a supporting frame, a movable impression die, a stationary impression bed, an oscillating lever for moving the die, a pin insertable axially into an aperture in the frame for pivoting the lever, and a spring cover plate for resilient engagement with the frame and with the pin whereby to prevent axial movement of the pin relative to the frame.

12. In a seal-press, a supporting frame, a reciprocating impression die, a stationary impression bed, two oscillating levers acting one upon the other to move the die, two medially reduced pins insertable axially into apertures in the frame for pivoting the levers, and a spring cover plate for resilient engagement with the frame and with the reduced portions of the pins whereby to prevent axial movement of the pins relative to the frame.

In testimony whereof I have hereunto signed my name.

HUGO S. HASSELQUIST.
